UNITED STATES PATENT OFFICE

ALVIN J. BRIGHT, OF CHRISTIANSBURG, OHIO

CARBURETOR

Application filed November 28, 1925. Serial No. 72,016.

This invention aims to provide novel means for regulating, in various ways, the supply of fuel in a carburetor.

It is within the province of the disclosure 5 to improve generally and to enhance the utility of devices of that type to which the invention appertains.

With the above and other objects in view which will appear as the description 10 proceeds, the invention resides in the combination and arrangement of parts and in the details of construction hereinafter described and claimed, it being understood that changes in the precise embodiment of the invention herein disclosed, may be made within 15 the scope of what is claimed, without departing from the spirit of the invention.

In the drawings:—

Figure 1 shows in side elevation, a device 20 constructed in accordance with the invention; Figure 2 is a longitudinal section, parts being omitted; Figure 3 is a top plan, the cover for the body of the carburetor being removed, and parts appearing in section; Figure 4 is a section taken through the float tank and attendant parts; Figure 5 is a bottom plan view of the cover for the float tank.

The carburetor forming the subject matter of this application includes a body 1 provided with an air inlet 4 and equipped, at 30 a point opposite to the air inlet 4, with a mixing chamber and outlet for the mixture, marked by the numeral 3. The flow of the mixture to the engine, from the chamber 3, is regulated by an adjustable throttle valve mechanism designated by the numeral 7. The body 1 has a detachable cover 5. The body 1 is supplied with an internal partition 33 located at the inner end of the mixing chamber 3. Within the body 1, a guideway 31 is fashioned, the guideway communicating with the air inlet 4 and with the mixing chamber 3 and being disposed at right angles to those elements. There is a small opening 2 in the bottom of the guideway 31, which serves as a vent and drain.

The numeral 19 marks a float chamber having a lateral extension 29 provided with a passage 54. The extension 29 of the float chamber 19 is detachably secured to the body

1, as shown in Figure 2. A nozzle 55 is disposed in the passage 54 and is threaded into the body 1, the nozzle discharging into the mixing chamber 3. A bore 6 establishes communication between the passage 54 and the nozzle 55 on the one hand, and the float chamber 19 on the other hand. A drain plug 30 is threaded into the part 29 of the float chamber 19, in alinement with the bore 6 and constitutes means whereby the float chamber 19 may be drained.

The float chamber 19 carries a detachable cap 8 in which a fluid inlet elbow 20 is mounted. A float 56 operates in the float chamber 19. Oppositely extended levers 49 are fulcrumed on pins 51 held by a securing device 52 in lugs 50 which project downwardly from the cap 8 of the float chamber 19. The levers 49 bear at their ends on the float 56, and, intermediate their ends, the levers 70 cooperate with the head 96 of a slidable valve 57 which controls the admission of fuel into the float chamber 19, through the fuel inlet 20.

The upper end of the nozzle 55 is controlled 75 by a first or fuel valve 18, in the form of a rod, movable in the cover 5 and in the partition 33. The valve 18 is threaded into a nut or rider 47 located within the body 1 of the carburetor.

The numeral 48 designates a lever, which may be called a first lever, the same having a forked end which is pivotally engaged with the rider or nut 47, the rider or nut being held against rotation by the forked end of the 85 lever. The lever 48 is supplied intermediate its ends with a depending projection 61. The fulcrum means for the inner end of the first lever 48 embodies an eccentric 43 formed on the head 75 of a shaft 24 journaled on an outstanding bearing 22 carried by the body 1. An arm 23 is adjustably secured, intermediate its ends, by a set screw 25, on the shaft 24, the body 1 being supplied with a stop lug 27, against which one end of the arm 23 abuts, under the action of a spring 26, the spring 26 being located about the bearing 22, one end of the spring being engaged with one stop lug 27, and the other end of the spring being engaged with the arm 23.

The depending projection 61 of the lever 48 bears upon the convexed edge 80 of a tapered cam member 46 which is pivoted at 81 to an internal arm 44 which is adjustably secured, by means of a set screw 45, to a shaft 16, mounted to rock in an outstanding bearing 11 on the body 1. An external arm 14 is adjustably held on the outer end of the shaft 16 by means of a set screw 17. The arm 14 carries an adjusting device 13, such as a screw, adapted to bear on a stop lug 15 carried by the body 1, the adjusting device being held against the stop lug by means of a spring 12 disposed about the bearing 11, one end of the spring being engaged with the stop lug 15, and the other end of the spring being engaged with the arm 14.

The cam member 46 has a lower concaved edge 82 resting on a finger 41 which forms part of a second lever 40, the lever 40 being fulcrumed on a screw 39 or like element, carried by the body 1 of the carburetor. The numeral 42 designates a coil spring disposed about the axis of the screw 39, one end of the spring engaging the partition 33, as shown in Figure 2.

The numeral 35 designates a cup-shaped air valve, which may be called a second valve, the same being slideable in the guideway 31, the valve 35 having a slot 36 receiving the lever 40. The valve 35 includes an inclined partition 37 with which the lever 40 cooperates, under the action of the spring 42. The valve 35 comprises a bottom 37 connected with the partition 83 by standards 84. The construction of the valve 35 is such that there is an opening 85 through it, the opening 85 in the valve communicating with the air inlet 4 and with the mixing chamber 3.

The general purpose of the valve 18 is to regulate the flow of fuel from the float chamber 19 to the mixing chamber 3, through the nozzle 55, responsive to engine suction, and the valve 18 has several adjustments.

The valve 18 may be rotated by hand, the valve moving endwise, because it is threaded into the nut 47. This adjustment admits enough fuel so that the engine will turn over nicely while it is running idle.

The valve 18 may be adjusted by way of the arm 23 and the shaft 24. When the shaft 24 is rotated, the eccentric 43, on the head 75 of the shaft, moves in an orbit, the lever 48 being swung, the fulcrum for the lever being the point of engagement between the projection 61 on the lever and the convexed edge 80 of the cam member 46, the lever being pivotally engaged with the rider 47 on the valve 18, and the valve being caused to move longitudinally. This is the ordinary acceleration adjustment which is made while the car is being driven, or when the engine is first started.

It is to be observed that the edge 82 of the cam member 46 is struck on an arc of which

the element 39 is a center. By positioning the external arm 14 properly, by means of the screw 13, the shaft 16 may be rotated to a position in which the arm 44 and the pivotal mounting 81 of the cam 46 will be so placed that when the lever 40 is operated by the upward movement of the valve 35, the finger 41 will move along the lower edge 82 of the cam 46 without swinging the cam 46. The cam 46, under such conditions, is not responsive to the movement of the valve 35. This may be regarded as a zero position (shown in Fig. 2), from which an adjustment may be begun, which will render the cam 46 responsive to the movement of the valve 35 through the instrumentality of the lever 40 and its finger 41. In order to effect such an adjustment, rotation is imparted to the shaft 16 by way of the screw 13 and the arm 14, the arm 44 swinging the cam 46, with the end of the finger 41 as a fulcrum, to such a position that when the valve 35 rises, the lever 40 and its finger 41 will swing the cam 46 on its pivotal mounting 81. The tilting or swinging movement which is imparted to the cam 46 from the screw 13, by way of the arm 44, is a hand adjustment, and the relative positions of the parts 61, 41, 44, 46, and 16, and the curve shown at 80, are so worked out that this hand adjustment may be made without making any appreciable change in any other adjustment.

The finger 41 constitutes a fulcrum for the cam 46, and by rocking the cam 46 on the finger 41, so that the free end of the cam is moved closer to the pivot 39 of the finger 41, the valve 18 is caused to rise when the valve 35 rises, thus increasing the flow of fuel. Owing to the specific curve of the lower edge of the cam 46, a neutral point is obtained in which the valve 35 will rise and fall without imparting movement to the valve 18.

The air passing through the inlet 4, through the transverse opening 85 in the valve 35 and through the mixing chamber 3, raises the valve, owing to the inclination of the partition 37, the valve tilting the lever 40, the finger 41 of the lever cooperating with the concaved edge 82 of the cam member 46, the cam member swinging with the pivot point 81 as a fulcrum, the parts 61, 48 and 47 operating the valve 18. This movement takes place automatically, responsive to engine suction.

One of the principal virtues of the carburetor, is that it provides a means whereby a proper mixture may be obtained for all practical speeds at which the engine may be running.

What is claimed is:—

A carburetor including a body having a fuel inlet, a first valve controlling the fuel inlet, an air inlet for the body, the body being provided with an outlet for the fuel mixture, a second valve mounted between the air inlet and the outlet, for right-line reciproca-

tion and including an inclined portion, a shaft mounted to rock in the body, the shaft being provided with an eccentric, a first lever mounted pivotally on the eccentric, a second lever fulcrumed on the body and slidably engaged with the inclined portion of the second valve, to be actuated thereby, a cam member engaged between the levers, means for operating the shaft to tilt the first lever on the cam member, a second shaft mounted to rock in the body, an arm on the second shaft, the cam member being pivoted to the arm, means for rocking the second shaft, and mechanism for connecting the first lever and 15 the first valve pivotally, the said mechanism including means for adjusting the first valve with regard to the fuel inlet, independently of the first lever, the inclined portion of the second valve being so placed that air passing 20 from the air inlet to the outlet will engage said inclined portion and operate the second valve.

In testimony that I claim the foregoing as my own, I have hereto affixed my signature.
